UNITED STATES PATENT OFFICE.

VINCENT BENDIX, OF CHICAGO, ILLINOIS.

ENGINE-STARTER.

1,287,616.

Specification of Letters Patent. Patented Dec. 17, 1918.

Application filed October 30, 1916. Serial No. 128,479.

To all whom it may concern:

Be it known that I, VINCENT BENDIX, a citizen of the United States, residing at Chicago, in the county of Cook and State 5 of Illinois, have invented certain new and useful Improvements in Engine-Starters, of which the following is a specification.

My invention relates to that type of engine starter exemplified in patents heretofore issued to me, for instance Patent No. 1,125,935, dated January 26, 1915, and Patent No. 1,172,864, dated February 22, 1916, which starters are characterized by a prime mover such as an electric motor, and a transmission or drive for transmitting the power of the motor by means of a rotatable screw shaft and a pinion mounted thereon, to a member of the engine to be started, such as the fly wheel thereof. This drive comprises a screw shaft operated either directly 10 or indirectly by the motor and the pinion screw-threaded on such shaft and having longitudinal movement thereon and rotary movement therewith.

My invention pertains to means for preventing creeping movement of the pinion on the screw shaft due to vibration of the automobile on which my engine starters are commonly employed, such means being arranged to prevent any possible slight rotation of the pinion or shaft which might advance it into contact with the fly wheel and thereby cause a clashing and a rasping sound, such means being so designed as not 25 to interfere in any manner with the ordinary or normal operation of the drive.

In the drawings, Figure 1 is an elevation of a drive showing my invention incorporated therein; and Fig. 2 a sectional elevation on the line 2—2 of Fig. 1 looking in the direction of the arrow and showing the spring in its compressed condition.

The general construction of the drive is the same as shown in my patents aforesaid 45 and it will therefore be sufficient to say that the same comprises in connection with the extended armature shaft 1 of an electric motor indicated at A a rotatable hollow screw shaft 2, a pinion 3 screw-threaded upon the 50 screw shaft adapted to mesh with the teeth 4^a of the fly wheel at 4, a coiled spring 5 constituting the resilient driving connection between the collar 6, secured to the armature shaft by the pin 7, and the bolt 8, 55 which screws into the enlargement 2^a of the screw shaft.

The pinion 3 is shown in the drawings in its retracted or home position. When the armature shaft and consequently the screw shaft is rotated this pinion is advanced automatically in a direction longitudinally of the screw shaft and into mesh with the teeth of the fly wheel. This longitudinal movement is stopped by the contact of the pinion 60 against the stop nut or collar 9 which is secured to the inner end of the screw shaft and adjacent the starting motor. At this time the pinion takes up the rotary movement of the screw shaft and drives the fly wheel. After the gas engine has started on 70 its own power the pinion is automatically moved to its home position shown.

The means provided for preventing possibility of rotary movement of the pinion 3 on the screw shaft due to vibration consists 75 of a helical spring 10 of rather light construction and surrounding the screw shaft at the inner end thereof between the pinion 3 and the stop nut or collar 9. This spring is anchored in a suitable manner at one end 80 to the stop nut and projects outwardly toward the pinion, the free end of the spring being preferably a slight distance away from the pinion when the latter is in its home position, as is shown in Fig. 1. As stated, 85 this spring is anchored in a suitable manner to the stop nut and as shown, the extreme inner end of the spring is bent at an angle and inserted in the hole 9^a of such nut. It will be observed that the spring being 90 thus fastened to the stop nut is rotatable therewith and consequently with the screw shaft.

In case of partial rotation of the pinion or screw shaft due to vibration, such pinion 95 will come into contact with the outer free end of the spring which will offer sufficient resistance to prevent any further rotation and consequent creeping of the pinion toward the fly wheel gear. This spring is 100 of such slight tension that it does not interfere with the regular or normal operations of the pinion. Moreover, when the pinion is in its driving position in full mesh with the fly wheel gear the spring occupies the 105 space represented by the width of the stop-nut and surrounds such nut.

I claim:

1. In a drive of the character described, the combination of a rotatable member, a 110 driving member mounted thereon for rotary movement therewith and longitudinal

movement thereof, a spring mounted on such rotatable member and arranged in the path of movement of the driving member for preventing accidental longitudinal movement of the latter, and stop means independent of the spring for stopping the longitudinal movement of said member.

2. In a drive of the character described, the combination of a rotatable member, a driving member mounted thereon for rotary movement therewith and longitudinal movement thereof, a coiled spring encircling such rotatable member and anchored at one end thereto and having its free end arranged in the path of movement of the driving member for preventing accidental longitudinal movement of the latter, and stop means independent of the spring for stopping the longitudinal movement of said member.

3. In a device of the character described, the combination of a rotatable screw shaft, a pinion screw-threaded thereon for rotary movement therewith and longitudinal movement thereof, a coiled spring encircling such screw shaft and arranged in the path of movement of the pinion, and stop means independent of the spring for stopping the longitudinal movement of the pinion.

4. In a device of the character described, the combination of a rotatable screw shaft, a pinion screw-threaded thereon for rotary movement therewith and longitudinal movement thereof, a stop nut on the screw shaft,

and a spring encircling the shaft and of greater diameter than the nut and arranged in the path of movement of the pinion.

5. In a device of the character described, the combination of a rotatable screw shaft, a pinion screw-threaded thereon for rotary movement therewith and longitudinal movement thereof, a stop nut on the screw shaft, and a coiled spring encircling the screw shaft and the nut, said spring being arranged in the path of movement of the pinion.

6. In a device of the character described, the combination of a rotatable screw shaft, a pinion screw-threaded thereon for rotary movement therewith and longitudinal movement thereof, a stop nut on the screw shaft, and a coiled spring encircling the screw shaft and the nut and anchored at one end to the latter, said spring being arranged in the path of movement of the pinion and adapted to be compressed thereby within the compass of the nut.

7. In a device of the character described, the combination of a rotatable screw shaft, a pinion screw-threaded thereon for rotary movement therewith and longitudinal movement thereof, a stop nut on the screw shaft, and a coiled spring encircling the screw shaft and the nut, said spring being arranged in the path of movement of the pinion and adapted to be compressed thereby within the compass of the nut.

VINCENT BENDIX.
